ERVIN G. BAILEY, OF CLEVELAND HEIGHTS, OHIO, ASSIGNOR, BY MESNE ASSIGNMENTS, TO FULLER LEHIGH COMPANY, A CORPORATION OF DELAWARE.

FURNACE AND LINING MATERIAL THEREFOR.

Application filed August 26, 1924. Serial No. 734,333.

This invention relates to furnace construction and refractory lining material therefor, and is shown embodied in a boiler furnace. The purpose of the invention is to secure a 5 serviceable and durable furnace construction which will withstand a high temperature and the destructive action of high velocity flame travel and impingement of fine particles of molten ash, such as is encountered in large 10 furnaces burning gases or pulverized solid fuel.

In the large furnaces which in recent years have been constructed for large steam plants, and especially those in which powdered coal 15 is used as a fuel, it has been found that with the best refractory materials and best construction available, the furnace walls have been very short lived, owing largely to the fluxing of the ash and the rapid wearing 20 away of the furnace wall when subjected to the high temperature and violent movement of the gases and ash particles resulting from the use of pulverized solid fuel.

The rapid deterioration of the furnace 25 walls and the cost of renewing them have constituted a very serious drawback to the use of powdered coal as a fuel, although in some respects it has a marked advantage over solid fuel and the stoking and burning 30 appliances employed in connection therewith.

A furnace wall composed mainly of water tubes, while being more durable than one made of refractory masonry, is objectionable 35 because it keeps the furnace wall at too low temperature for most effective combustion of the fuel.

In accordance with the present invention, the furnace wall is composed in part of water 40 tubes which supply the structural strength for the wall, said tubes being used in conjunction with a novel lining material consisting of a composite tile formed in part of refractory material and in part of cast iron 45 or equivalent material intimately united to the refractory portion and together therewith constituting a unitary tile.

The refractory portion of the tile is substantially like the face portion of an ordinary tile or brick such as is used in refractory masonry, while the metallic portion, of cast iron, is shaped with reference to the tubes which constitute the structural frame

work of the furnace wall so that the metallic portion of the tile will seat upon a considerable portion of the surface of one or more of the tubes, and the tile also has provision for clamping or fastening each tile independently in place with its metallic portion in contact with the tubes.

In the completed furnace wall the tiles are clamped or fastened to the tubes so as to be in contact with one another around their marginal parts, and the tiles are set with the refractory face portion at the inside of the furnace, which thus is completely lined with refractory material and may have much the same appearance as if composed wholly of refractory material such as the bricks or tiling in the usual construction of furnace 70 walls.

The refractory portion of the lining of the furnace is, however, relatively quite thin, and together with the metallic portion to which it is intimately united, and which lies in firm, intimate contact with water tubes, affords a good heat conductor from the interior exposed face of the lining to the water in the tubes.

By this construction the heat is conducted 80 from the refractory material to the water with sufficient rapidity to prevent the refractory material from being heated to a temperature sufficient to weaken it, or to result in the fusion of ash and slag upon it, so that it is 85 extremely durable as compared with the usual refractory wall construction, but as contrasted with a water tube wall it attains a sufficiently high temperature to keep the combustion of the fuel and gas in a state 90 of good efficiency.

The heat which is thus conducted away 95 from the refractory portion of the wall is almost entirely imparted to the water in the tubes and thus serves the purpose of generating steam without substantial waste of heat.

In the accompanying drawing, Fig. 1 represents the side wall of a furnace of a construction embodying this invention, a portion of the outer portion of the wall being shown as broken away to show the water tubes and the refractory lining material secured thereto.

Fig. 2 is a side elevation of the tiles as 105 they adjoin one another in the furnace wall,

a portion of one of the said tiles being shown in longitudinal section.

Fig. 3 is an elevation of one of the tiles showing the rear or back portion which is 5 to be in contact with the tubes; and

Fig. 4 is a horizontal section of a portion of the furnace wall, one of the tiles being shown in section on line α^2 of Fig. 3 and the other tiles of the course in plan.

10 In the illustrated example of the invention the side wall of the furnace is composed of a number of vertical water circulating tubes 2 connected at the lower end with a header or manifold, 3, into which the cooler water 15 is introduced, and at the upper end with the water space of the boiler in any suitable way for securing the circulation of water through the tubes as in common practice.

The spaces between the vertical tubes 2 20 are closed and the furnace is provided with a continuous refractory lining by the employment, in conjunction with the tubes, of refractory tiling composed of composite tiles of a construction such as is represented in 25 Figs. 2, 3 and 4.

Each tile is composed of a facing member 10 of refractory material of substantial thickness and a backing or body portion 12 of metal intimately secured to or interlocked 30 with said facing member 10 of refractory material.

The proper union of the refractory facing member and metallic backing may be attained by first manufacturing the facing 35 member with suitable recesses and rabbets as shown, and then placing the same in a mold such as used for casting metals, having a cavity adjacent to the refractory portion of proper shape for the metallic portion of 40 the tile. The molten metal is then run into the mold and entering the cavities and rabbets of the tiling as shown at 14, 15, becomes completely interlocked therewith and forms intimate union with the refractory portion 45 throughout the entire contacting surface thereof.

The metallic backing or body portion of the tile is also formed with suitable seats 16 to fit and make a close contact with the pipes 50 2 against which the tiles are to be secured, said seats extending the full length of the tile and affording the maximum area attainable of contacting surfaces between the pipes and tiling.

55 In order to obtain maximum conductivity of heat from the refractory lining to the water in the tubes a lead or other soft metal gasket may be placed between the rough cast body portion of the tiling, and the rough 60 surface of the tubes as indicated at 13; this soft material being compressed into close and intimate contact with the surfaces between which it lies by the pressure of the devices employed for securing the tiling to 65 the pipes which will be hereafter described.

The interlocking metallic portions 14, 15, of the tile do not extend through the entire thickness of the refractory portion, which thus provides an uninterrupted layer of refractory lining material over its entire inner 70 surface, which is exposed at the inside of the furnace.

The rear metallic portion of the tile is also provided with a notched recess as shown at 17 to form a hold or anchorage for the 75 head of a bolt 18, by which the tile is secured to the tubes 2, a suitable saddle or clamp member 19 being interposed between the nut and the tubes 2 so that each tile unit is detachably secured to and supported by the 80 tubes substantially independently of the others.

The metallic portion of the tile is here shown as offset with relation to the refractory portion at the upper and lower edges 85 as best shown at 20, 21, Fig. 2, to afford an overlapping joint between the successive horizontal courses of the tiling and contribute to the rendering of the furnace wall 90 air tight.

While the tubes and tiling are sufficient for the wall structure, the wall is shown in Figs. 1 and 4 as completed by a layer 30 of nonconducting material applied on the outside of the tiling and covered by plates 31 95 of sheet metal which are secured together and also secured to the furnace wall by some of the bolts 18 which are extended through to the outside of the furnace as shown in dotted lines at 180, Fig. 4.

Some of the advantages of this construction of a boiler furnace have already been indicated. The composite tiling, when in place, affords by its face portion, a complete refractory lining or wall area for the furnace, superficially like that usually employed but of relatively small thickness as compared with the usual masonry wall, whether a solid wall or a hollow air-cooled wall. The intimately united interlocked 105 metallic portion 12 affords adequate strength and support for the relatively thin refractory material, and also rapidly conducts the heat therefrom to the water in the circulating tubes 2 against which the tiles 110 are clamped.

The refractory portion of the lining becomes heated to a sufficiently high temperature to maintain the combustion in the furnace with efficiency, although it does not 115 become heated sufficiently to be weakened and gradually disintegrated, as is the case with a solid masonry wall.

The tiles being separate units, each individually supported upon the tubes, there 125 is no trouble from expansion, and the refractory material itself has no burden to carry and is not subject to any mechanical stress.

The use of the tiling obviously is not lim- 130

ited to boiler furnaces, and for other uses the metallic body portion may be properly shaped to co-operate with the circulating cooling medium, whatever it may be, and to 5 be secured to the framing or structural body portion of the wall to meet the conditions which may be encountered.

It is to be understood that the form, size, and proportion, of the components of the 10 tile may be widely varied without departing from the invention, and that tiling of similar character and in similar structural relations may be used for other purposes than for the construction of furnace walls. For 15 example, tiling of this nature might be incorporated in a superheater of a construction in which the composite tiles are secured to pipes or ducts containing dry steam. In such construction the tiling would protect 20 the steam ducts from excessive heat which would be detrimental to them if exposed to a very high temperature; thus enabling the superheater to be used at locations in the furnace which would be unsafe unless protected in some way.

The thickness of the refractory portion of the tiling may be varied according to the conditions in which the tiling is to be used. For example, with some grades of fuel the 30 tiling can withstand a much higher temperature safely than with certain other grades. It is desirable that the thickness should be such as to keep the temperature two or three hundred degrees lower than 35 the fusing temperature of the ash of the fuel that is to be used, so that even though the ash is flying through the furnace in small particles in a molten state, it will not adhere to the refractory lining, or if it should 40 adhere in some cases, it would be of a spongy nature which can readily be removed without injury to the refractory surface.

Claims:

1. A furnace wall comprising a series of 45 circulating tubes constituting the structural sustaining component of the wall, combined with lining tiles each provided with seats to fit and make extensive contact with the tubes and each having provision for being independently clamped into firm contact with said tubes and gaskets of soft metal interposed between said seats and tubes.

2. A furnace wall comprising a row of 55 spaced cooling tubes and a plurality of tile positioned edge to edge and connected to and supported by said tubes to form a substantially continuous wall area, each of said tile comprising a refractory furnace facing member, and a metallic backing therefor 60 having its front face in intimate thermal contact with the rear face of the refractory member and a relatively large portion of

its rear face in intimate thermal contact with at least one of said tubes.

3. A furnace wall comprising a row of 65 spaced cooling tubes and a plurality of tile positioned edge to edge and connected to and supported by said tubes to form a substantially continuous wall area, each of said tile comprising a refractory furnace facing 70 member, a metallic backing therefor having its front face in intimate thermal contact with the rear face of the refractory member and a relatively large portion of its rear face in intimate thermal contact with at 75 least one of said tubes, and clamping means for each tile to draw the metallic backing thereof toward and into intimate thermal contact with said tubes.

4. A furnace wall comprising a row of 80 spaced cooling tubes and a plurality of tile positioned edge to edge and connected to and supported by said tubes to form a substantially continuous wall area, each of said tile comprising a refractory furnace facing 85 member, a metallic backing therefor having its front face in intimate thermal contact with the rear face of the refractory member and a relatively large portion of its rear face in intimate thermal contact with at 90 least one of said tubes, and clamping means for each tile to draw the metallic backing thereof toward and into intimate thermal contact with said tubes, said means comprising a member contacting with the rear side 95 of said tubes and a bolt extending between said member and said metallic backing.

5. A furnace wall comprising a row of spaced cooling tubes and a plurality of tile positioned edge to edge and connected to and supported by said tubes to form a substantially continuous wall area, each of said tile comprising a refractory furnace facing member, and a metallic backing therefor 100 having its front face in intimate thermal contact with the rear face of the refractory member and a relatively large portion of its rear face in intimate thermal contact with at least one of said tubes, the metallic 105 backings of adjacent tile being spaced apart a greater distance than the corresponding refractory members.

6. A furnace wall comprising a row of spaced cooling tubes and a plurality of highly heat-conductive tile positioned edge 115 to edge to form a substantially continuous wall area, each of said tile having intimate thermal contact with at least one of said tubes, and means to connect said tile to said tubes, said means being adapted to permit independent attachment and removal of any 120 of said tile.
